SAFETY SWITCH PLATE

Frank Emery Tiffany, Los Angeles, Calif., assignor to Tiffany Technical Corporation, Los Angeles, Calif., a corporation of California

Application December 7, 1933, Serial No. 702,310

4 Claims. (Cl. 200—167)

My invention relates to safety switch plates and acts as an electric safety indicator by means of gas-ionization developed in a non-consuming, two electrode gas bulb which is an integral part 5 of my safety switch plate.

The object of my invention is to determine, by sight in a dark room, the location of electric light switches and of electric switches of any other kind so as to guide persons entering the room to the 10 position of said electric switches.

A further object of my invention is to indicate whether such electrical switches located either in the same room with the safety switch plate or in an independent and different place, are in their 15 "open" or "closed" position, thereby the safety switch plate serving as a checking device upon electrical circuits.

Referring to the accompanying drawing my invention may be exemplified by the following description and exhibition.

Fig. 1 shows my safety switch plate in front elevation. Fig. 2 is a longitudinal cross section of Fig. 1. Fig. 3 is a back view of Fig. 1. Fig. 4 demonstrates the operation of the device by means 25 of a circuit diagram.

In the drawing 1 is the body of the safety switch plate made of any suitable material. 2 is a hole through the plate 1 and acts as a window for the indicator device 6 which is, in this example, located within a semicylindrical protuberance 3 carried by the plate 1. The body of the switch plate may be fixed to walls and building frames by means of screws inserted through screw holes 4. This provision renders the invention fit and 35 applicable in place of any standard electric wall switch plates presently in use and provides for a quick replacement of standard switch plates by my safety switch plate, without any essential change in the wiring. The switch handle itself 40 protrudes, for operability, through handle hole 5.

Behind opening 2 is a transparent or translucent plate 7 following the semi-cylindrical shape of the opening and being placed between the opening and the indicator device 6. 7 may be 45 colored.

As an integral part of the switch plate, indicator device 6 is immovably fixed within the semi-cylindrical protuberance 3 of the plate 1. The indicator device consists of a gas bulb containing 50 any suitable gas at low pressure and also containing two electrodes, shown at 15 in Fig. 4, which electrodes terminate, through flexible leads 8 and 9, that may be easily and quickly attached to terminals 10, of the switch circuit. When so attached a shunt circuit will be established around 55

the switch 11 from its terminal 10 in which the gaseous bulb 6 is included.

The operation of the device is as follows: As shown in Fig. 4, the indicator bulb is shunted across the switch terminals of any electrical switch in connection with which the safety switch plate is desired to be used. This shunting is obtained by connecting the terminals 10 of bulb 6 to the switch terminals of switch 11 which serves to close and open an electric circuit fed from terminals 13, across line 14 and current consumer 12 of which 16 is the consuming resistance. When switch 11 is in its open position, as shown in Fig. 4, the indicator bulb 6 is connected in series in circuit 13, 14, 16, 8, 6, 9, 13. The electrodes 15, 15 however, do not constitute a direct wire connection and are placed within bulb 6 in such a way that at the available potential difference existing between them they effect ionization of the 20 gas enclosed in the bulb, thereby creating a visible glow which may be viewed through plate 7 and window opening 2, thus indicating that the consuming device 12, 16, which latter now acts only as a circuit resistance, is not in operation 25 and showing, at the same time, the location of the switch or switch box.

While the switch is in its "open" position, as described hereinbefore, the ionization current through bulb 6 is so low, as a result of geometrical and assembly arrangement of the bulb, that no 30 appreciable current is consumed and the indicator may be left in this indicating position, that is with open switch, indefinitely without any expense.

At the moment switch 11 is closed, the indicator bulb 6 is shunted by switch 11 and no ionization current can develop. The indicator bulb is dark now and this is the sign of the consumer 16 being operated.

An important feature of my invention resides 40 in the fact that my switch-plate with its gaseous light bulb may be sold as a complete unit to be substituted for existing switch-plates without necessitating a change in the installed wiring circuits. This is made possible from the fact 45 that the flexible leads connected with the electrodes of the gaseous bulb of my invention are of sufficient length to permit them to be attached to the circuit terminals 10 of the switch 11, shown in Fig. 4. When so connected the 50 gaseous bulb 6, will be included in a shunt circuit leading around the switch terminals 10. Therefore when the switch 11, is moved across the terminals 10, to complete the main circuit through the house lights 12, the gaseous bulb 55

- located in the shunt circuit will not be lighted, and when the switch is moved to its other position to extinguish the house lights, the shunt circuit through the gaseous bulb will be open and the bulb will become lighted or will glow but without consuming an appreciable amount of current. Thus, when the house lights are on, the gaseous bulb will be off and vice versa. These results are accomplished with my invention without any change in the installed house wiring system, and my switch-plate with its gaseous bulb as described may be sold as a unit to be substituted for existing plates or employed as a new installation.
15. What I claim is:
1. A switch-plate of the character described, having an outwardly extending housing provided with a sight window and said plate having a plurality of openings through which fastening devices and a switch operating member may extend, the front and end walls of the housing being formed integral with the plate and located within the marginal edges thereof, and a gaseous light bulb supported within said housing in rear of its window, said bulb having its electrodes terminating in flexible lead wires adapted to be readily attached to the terminals of an electric switch circuit located in rear of the said plate to provide a shunt circuit in which the gaseous bulb is included, the construction and arrangement being such that no part of the bulb or its lead wires projects beyond the upper edge of the plate.
  2. In combination with an electric switch and its terminals, a switch plate of the character described provided with an integral housing having a sight window and said plate having a plurality of openings through which fastening devices and a switch operating member may extend, said housing located within the marginal edges of the plate and having closed ends, and an elongated gaseous light bulb positioned in said housing in rear of said window, the current lead wires for the bulb electrodes extending through the opposite ends of the bulb and said

lead wires terminating in flexible leads, the ends of which are of sufficient length to be readily attached to the switch terminals of an electric switch circuit located in rear of the said plate to establish a shunt circuit in which the gas bulb is included, the construction and arrangement being such that no part of the bulb or its lead wires extends beyond the upper edge of the plate, whereby said edge may make contact with the wall to which the plate is attached.

3. In combination with a switch plate having an integral outwardly protruding wall constituting a light bulb housing provided with a window opening and said plate having other openings to receive plate securing means and a switch 15 operating member, the walls of the housing located within the marginal edges of the plate, a gaseous light bulb shaped to be positioned in the housing formed by said protruding wall and in rear of the window opening, said light bulb 20 having its electrode lead wires extending from the opposite ends thereof and terminating in flexible leads, the ends of which are adapted to be connected to the terminals of a switch circuit located in rear of the switch plate, thus 25 establishing a shunt circuit from said terminals in which the gaseous bulb is included, the construction and arrangement being such that the bulb and its lead wires will be entirely covered by the plate proper and its housing with no portion thereof extending beyond the upper edge of the plate.

4. A switch plate of the character described, having an integral outwardly extending wall protruding from its front face and all portions 35 of which are located within the marginal edges of the plate, said wall having a sight window and the plate having a plurality of openings through which plate-fastening devices and a switch operating member may extend, said protruding wall providing a housing open at the rear of the plate and of less length than the width of the plate, said housing constructed to receive, house and support a gaseous light bulb.

FRANK EMERY TIFFANY. 45
